COMBINED FOOD TRAY AND PIVOTED BEVERAGE RACK

Robert B. Karoff, New York, N. Y., assignor to Karoff Originals, Ltd., New York, N. Y., a corporation of New York

Application November 20, 1952, Serial No. 22,384

Term of patent 7 years

(Cl. D44—10)

To all whom it may concern:

Be it known that I, Robert B. Karoff, a citizen of the United States and a resident of New York city, county and State of New York, have invented a new, original, and ornamental Design for a Combined Food Tray and Pivoted Beverage Rack, of which the following is a specification, reference being had to the accompanying drawings forming a part thereof, in which:

Fig. 1 is a top plan view of a combined food tray and pivoted beverage rack, embodying my new design;

Fig. 2 is a side elevational view thereof with tumblers being shown in dotted lines for the purpose of illustration;

Fig. 3 is a perspective view thereof as seen in a tilted position;

Fig. 4 is another perspective view thereof as seen when tilted in another position.

I claim:

The ornamental design for a combined food tray and pivoted beverage rack, as shown and described.

ROBERT B. KAROFF.
